R. L. OGDEN.

APPARATUS FOR EXTRACTING VALUES FROM BODIES.

APPLICATION FILED SEPT. 22, 1916.

1,215,182.

Patented Feb. 6, 1917.

UNITED STATES PATENT OFFICE.

RICHARD LESLIE OGDEN, OF RAHWAY, NEW JERSEY.

APPARATUS FOR EXTRACTING VALUES FROM BODIES.

1,215,182.

Specification of Letters Patent.

Patented Feb. 6, 1917.

Application filed September 22, 1916. Serial No. 121,590.

To all whom it may concern:

Be it known that I, RICHARD L. OGDEN, a citizen of the United States, and a resident of Rahway, in the county of Union and State of New Jersey, have invented a new and Improved Apparatus for Extracting Values from Bodies, of which the following is a full, clear, and exact description.

Among the principal objects which the present invention has in view are: to continuously extract by leaching the soluble values of neutral bodies; to perform the above-mentioned operation at reduced cost; and to provide a prime mover for performing the mechanical part of the process automatically and inexpensively.

Drawings.

Figure 1 is a vertical section of an apparatus of the character mentioned constructed and arranged in accordance with the present invention;

Fig. 2 is an enlarged detail view in vertical section of a feed valve employed by the prime mover used in actuating the apparatus;

Fig. 3 is a detail view on an enlarged scale showing the latch for operating the valve-actuating device.

80

Description.

As seen in the drawings, a suitable chemical-bearing body 8 is placed in a colander 9 upon a sieve bottom 10 therein. The sieve bottom 10 is supported in spaced relation to an inclined bottom 11 with which the said colander is furnished. The bottom 11 drains to a delivery pipe 12 which is controlled by a valve 13. The valve 13 is only used when the operation of the apparatus is initiated. After the operation has progressed, the valve 13 is opened and thereafter remains so. Liquid which passes through the pipe 12 is free to enter at all times the vat 14.

The solvent is delivered from the retort 15 through a pipe 16 which is operatively connected with one or more spray pipes 17. The pipes 17 are superposed over the body 8 so that the solvent delivered to the colander is evenly sprayed over the said body.

The nature of the solvent depends upon the nature of the body 8. In all performances of this apparatus it will be understood that the solvent is suitably related to the soluble matter contained in the body 8.

The solvent is passed from the retort 15 to the colander 9 by pressure developed in the retort 15 by the operation of a float 18 in a closed tank 19. The upper portion of the tank 19 is sealed so that air pressures may be developed in the said upper portion. This portion of the tank 19 is operatively connected with the retort 15 and is always held in open communication by means of the pipe 20 which is utilized for equalizing the pressures in the tank 19 and the retort 15. The float 18 is elevated and depressed in the tank 19 in correspondence with the rise and fall of the water 21 which is introduced thereto near the bottom thereof from the pipe 22, which pipe is connected to a suitable source and the flow through which is controlled by a valve 23.

The water 21 when introduced into the tank 19 operates a piston for compressing the air in the upper portion of the said tank.

The float 18 supports a rod 24 from which extend fingers 25 and 26 used for operating the valve 23 to open and close the same. The distance between the fingers 25 and 26 is varied and regulated to permit more or less water to enter the tank 19. The valve 23 has a head or washer 27 at the end of a plunger 28. The plunger 28 is operatively connected by a pin 29 with a weighted lever 30. The lever 30 is fulcrumed on the pin 31 and bracket 32. A weight 33 is mounted at the end of the lever 30 and is adjustable lengthwise thereof to regulate the closing pressure of the head 27 on the seat formed at the end of the outlet passage 34 of the valve 23.

The free end of the lever 30, as shown best in Fig. 3 of the drawings, is held under a latch head 35 of the latch 36. To facilitate the operation of the latch 36 and the lever 30, the said latch is furnished with a series of wheels 37 to form a pathway for the lever 30 when the same is forced down on the inclined plane formed by the said wheels, by a finger 26. The finger 26 engages the lever 30 when the float 18 is near the bottom of the tank 19, and the said finger depresses the said lever sufficiently to pass under the latch head 35 prior to the float 18 engaging the bottom of the tank 19.

In the position shown in Figs. 1 and 3 of the drawings, the head 27 is lifted and water is permitted to flow freely through the valve 23 to the pipe 22 and thence enters the tank 19. The finger 25, as indicated in Fig. 3 of the drawings, ascends in correspondence

with the rise of the float 18, and passes over the shoulder 38 with which the head 36 is provided and in a position to engage the said shoulder. When thereafter the water 21 is drawn from the tank 19, the finger 25 in descending with the float 18 presses upon the shoulder 38 to rock the latch 36 on its pivot pin 39 until the latch 36 releases the lever 30. The lever 30 being thus released by the latch 36, the weight 33 rocks the lever 30 and seats the head 27 to close the outlet passage 34. Immediately the finger 25 is passed out of contact with the latch 36, the weighted end 40 rocks the latch to its initial position where 15 it is stopped by the pin 41.

The water 21 is drawn off from the tank 19 to an auxiliary tank 42, wherein a float 43 is contained. The float 43 when lifted exposes the receiving end of a waste pipe 44. 20 The float 43 supports a tube 45, the lower end whereof closes an inlet orifice 46 for delivery of water to the tank 42.

Normally the orifice 46 is sealed by a flared end 47 of the tube 45 at the lower end of a 25 chamber 48. From the sides of the chamber 48 are supported rings 49 which guide the tube 45 when lifted by the float 43. The chamber 48 is in open communication with the tank 19, an orifice 50 being provided for 30 this purpose.

To insure the lift of the float 43, the same is provided with a central chamber 51. The chamber 51 normally holds the delivery end of the pipe 44 which is raised above the bottom of the tank 42 to a height to overflow which the water in the tank 42 must have risen to a point where the float 43 is positively raised.

The purpose in this construction is to insure 40 the lift of the end 47 from its seat closing the orifice 46 and to establish a freer communication between the tanks 19 and 42. The supply of water through the orifices 46 and 50 is greater than the capacity of the 45 pipe 44, and so long as the water continues to pass from the tank 19 to the tank 42, the elevation of the float 43 is insured.

After the water in the tank 42 has been drained to a level with the receiving end of 50 the pipe 44, the remainder of said water is drawn off by a small siphon 52, the receiving end whereof as seen best in Fig. 1 of the drawings, is approximate to the bottom of the tank 42.

55 Back flow in the pipes 16 and 53 is prevented by ball-check valves 54 and 55. Both valves are disposed at the entrance ends of the pipes 16 and 53 to freely admit the solvent 56 contained in the retort 15 and the 60 solution 57 in the vat.

The vat 14 has a draw-off cock 58 and a sampling pet cock 59. Attached to the pet cock 59 is a sight gage 60 for determining the height of the solution 57 and in some 65 cases the color thereof. Samples of this so-

lution may be drawn off by the pet cock 59, and when the solution has reached the desired content, it is drawn from the vat 14 through the cock 58, manipulating the valve 61 to this end.

If the solution is to be heated a suitable brazier is placed in the frame or support 62. If desired, the solution may be heated by steam, the coils to be contained within the retort 15 or exterior thereto.

Operation.

The colander 9 is first charged with the body 8 carrying the soluble values which are to be extracted therefrom. The retort 15 is then charged with a suitable solvent. If the solvent is to be heated, provision is made to that end.

The valve 23 if closed is now opened. The floats 18 and 43 are both at their lowest positions and the tube 45 is arranged to close the orifice 46.

When the water enters the tank 19, the air contained in the tank is trapped at the upper end thereof and is gradually compressed by the rising water. The pressure in the tank 19 and the retort 15 is equalized by free communication through the pipe 20.

When the pressure in the retort 15 is sufficient the solvent 56 passes into the pipe 16, displacing the ball valve 54. The solvent is delivered from the pipe 16 to the distributing pipes 17 to be sprinkled over the body 8. The soluble component of the body 8 is extracted therefrom. The liquid percolates through the body 8 and the perforations in the sieve 10 to be gathered on the bottom 11 and delivered by the pipe 12 to the vat 14.

The air pressure in the tank 19 continues to increase until the float 18 carries the finger 25 above the shoulder 38, and until the level of the water 21 in the chamber 48 rises above the upper end of the tube 45. The water then overflows the said tube and passes therefrom through the orifice 46 to the auxiliary tank 42.

When sufficient water has thus passed through the tube 45 to raise the water level in the tank 42 to the point of buoying the float 43, the tube 45 is lifted and the end 47 moved from the orifice 46. The water 21 then flows rapidly into the tank 42, lifting the float 43 to its upper limit. Water now flows freely from the tanks 19 and 42 through the waste pipe 44, and continues to so flow until the tank 19 is completely emptied and the water level in the tank 42 descends below the upper end of the pipe 44. The office of the siphon 52 is now called into play, when the water remaining in the tank 42 is siphoned over to the pipe 44 and the float 43 is permitted to settle to a point where the end 47 completely closes the orifice 46.

Concomitant with the passing of the

water 21 from the tank 19, the float 18, rod 24, and finger 25 descend, the latter dropping the latch 36 to release the lever 30. This permits the weight 33 to close the valve 23. When the float 18 and parts connected therewith approach the lower extreme of their movement, the finger 26 engages the lever 30 to depress the free end thereof upon the inclined track formed by the wheels 37. The latch 36 is deflected until the lever 30 passes to a position where the latch 36 may rock to dispose the head 35 above the said lever 30. With the opening of the valve 23, the filling operation of the tank 19 reoccurs. The effect of the compression of the air by the introduction of water into the tank 19, has been mentioned. When the water is drawn from the tank 19, the compressed air is rarefied due to the displacement of the solvent 56 in the retort 15. As the solution 57 fills the vat 14, air pressure is avoided therein by providing the escapement pipe 63. When now the above-noted rarefaction occurs the solution 57 is drawn over by way 25 of the pipe 53 to the retort 15 until the quantity of liquid in said retort is substantially that which said retort initially contained.

It will be noted that this action is in the nature of respiration. This automatically continues until the attendant by sampling or otherwise, detects the completion of the operation, when the valve 23 is maintained closed and the solution is decanted from the vat 14.

Claims:

1. An apparatus for extracting soluble constituents from solids comprising a container for solvent; a container for soluble bodies; a container for solution; means for operatively connecting said containers *in seriatim* for establishing a circulation of liquids progressively in the order named under suitable conditions; a plurality of pipes connecting said first-mentioned and second-mentioned containers, and said third-mentioned and first-mentioned containers, said pipes being provided with check valves for controlling the flow through said pipes in one direction only; and means for alternately increasing and decreasing the atmospheric pressure in the first-mentioned container.

2. An apparatus for extracting soluble constituents from solids comprising a container for solvent; a container for soluble bodies; a container for solution; means for operatively connecting said containers *in seriatim* for establishing a circulation of liquids progressively in the order named under suitable conditions; a plurality of pipes connecting said first-mentioned and second-mentioned containers, and said third-mentioned and first-mentioned containers, said pipes being provided with check valves

for controlling the flow through said pipes in one direction only; and means for alternately increasing and decreasing the atmospheric pressure in the first-mentioned container, said means embodying an air compressor in open communication with said first-mentioned container, and means automatically operable in correspondence with said compressor for increasing and reducing the pressures therein alternately.

3. An apparatus for extracting soluble constituents from solids comprising a container for solvent; a container for soluble bodies; a container for solution; means for operatively connecting said containers *in seriatim* for establishing a circulation of liquids progressively in the order named under suitable conditions; a plurality of pipes connecting said first-mentioned and second-mentioned containers, and said third-mentioned and first-mentioned containers, said pipes being provided with check valves for controlling the flow through said pipes in one direction only; an air tank in open communication with said first-mentioned container; a water piston for said air tank; means operable by said piston for suspending the operation of said piston; and means for reciprocating said piston in said tank for increasing and diminishing the pressure in said first-mentioned container successively.

4. An apparatus for extracting soluble constituents from solids comprising a container for solvent; a container for soluble bodies; a container for solution; means for operatively connecting said containers *in seriatim* for establishing a circulation of liquids progressively in the order named under suitable conditions; a plurality of pipes connecting said first-mentioned and second-mentioned containers, and said third-mentioned and first-mentioned containers, said pipes being provided with check valves for controlling the flow through said pipes in one direction only; an air tank in open communication with said first-mentioned container; a water piston for said air tank; means operable by said piston for suspending the operation of said piston; and means for reciprocating said piston in said tank for increasing and diminishing the pressure in said first-mentioned container successively, said means embodying a float, an auxiliary tank, said auxiliary and air tanks having open communication, and a valve controlling said communication, said valve being operable by said float.

5. An apparatus for extracting soluble constituents from solids comprising a container for solvent; a container for soluble bodies; a container for solution; means for operatively connecting said containers *in seriatim* for establishing a circulation of liquids progressively in the order named

under suitable conditions; a plurality of pipes connecting said first-mentioned and second-mentioned containers, and said third-mentioned and first-mentioned containers, 5 said pipes being provided with check valves for controlling the flow through said pipes in one direction only; an air tank in open communication with said first-mentioned container; a water piston for said air tank; 10 means operable by said piston for suspending the operation of said piston; means for reciprocating said piston in said tank for increasing and diminishing the pressure in said first-mentioned container successively, 15 said means embodying a float, an auxiliary tank, said auxiliary and air tanks having open communication, and a valve controlling said communication, said valve being operable by said float; and means for continuing 20 the flow of water from said auxiliary tank after the communication between said air and auxiliary tanks is closed.

6. An apparatus for extracting soluble constituents from solids comprising a container for solvent; a container for soluble bodies; a container for solution; means for operatively connecting said containers *in seriatim* for establishing a circulation of

liquids progressively in the order named under suitable conditions; a plurality of 30 pipes connecting said first-mentioned and second-mentioned containers, and said third-mentioned and first-mentioned containers, said pipes being provided with check valves for controlling the flow through said pipes 35 in one direction only; an air tank in open communication with said first-mentioned container; a water piston for said air tank; means operable by said piston for suspending the operation of said piston; means for 40 reciprocating said piston in said tank for increasing and diminishing the pressure in said first-mentioned container successively, said means embodying a float, an auxiliary 45 tank, said auxiliary and air tanks having open communication, and a valve controlling said communication, said valve being operable by said float; and means for continuing the flow of water from said auxiliary tank after the communication between said air 50 and auxiliary tanks is closed, said means embodying a siphon, the receiving end whereof extends below the flotation level of said float.

RICHARD LESLIE OGDEN.
